UNITED STATES PATENT OFFICE.

FREDERICK EUGENE PERNOT, OF LONDON, ENGLAND.

ALTERNATING-CURRENT SIGNALING SYSTEM.

Application filed November 6, 1924, Serial No. 743,060, and in Great Britain November 28, 1923.

This invention relates to improvements in alternating current signaling systems and has particular reference to those types of telegraph signaling systems wherein the signal elements are formed by trains of alternations of an alternating current. The invention has for its principal object to secure a more rapid rate of signaling, as well as greater certainty and precision in the formation of the signals. 5 The invention is applicable to those systems wherein a single alternating current either "per se" or in combination with direct current is used for the transmission of a single series of messages, as well as to those systems 10 wherein several alternating currents, either "per se" or in combination with direct current are used for the simultaneous transmission of a plurality of messages.

The principal feature of the present invention consists in the production, in alternating current signaling systems, of change of phase in the alternating current, or currents, used in the formation of the signal elements.

Another feature of the invention consists 25 in the provision of means in alternating current signaling systems whereby in signaling a change of phase is secured for each successive signal, whereby a better definition is obtained in the formation of the signal elements and thereby a higher possible speed 30 of signaling.

A further feature of the invention is found 35 in the provision of means whereby the signals which are characterized by currents of different phase are caused to actuate a receiving device in a manner dependent upon the phase of the alternating current comprising the signal.

A still further feature of the invention 40 consists in the provision of means whereby the received signals characterized by currents of different phase are caused to interact or co-act with locally produced periodic actions or force components in order to detect and/or 45 interpret the changes of phase of the signal current.

Yet another feature of the invention is found 50 in the provision of means operating in connection with signals characterized by currents of different phase whereby synchronism is maintained between the A. C. transmitting and receiving apparatus.

Another feature of the invention consists 55 in the utilization in an alternating current signaling system, of cable code signals, and in particular "block" cable code signals.

Subsidiary features of the invention comprise:—

a. The utilization of a mechanical, synchronously driven, rectifier for the reception 60 of alternating current signals;

b. The use of a receiving instrument having a synchronized alternating field for the purpose of receiving alternating current, 65 cable code signals;

c. The provision of means for maintaining a constant frequency in the transmitted alternating signal current; and

d. The provision of means for driving an 70 automatic transmitter in step with the alternating current source used for signaling.

By expression "change of phase" and by similar expressions is to be understood alteration of the phase by any required amount, but in particular by 180 degrees this particular degree of change amounting to phase reversal.

Further features of the invention will be apparent from the following description and accompanying figures, wherein:

Fig. 1, shows a system adapted to reverse the phase of successive alternating current Morse code signals by reversing the direction of alternator field current.

Fig. 2, depicts the types of A. C. signals 85 produced by the arrangement of Figure 1.

Fig. 3, shows a system adapted to reverse the phase of successive Morse code signals by reversing the output leads of an A. C. generating source.

Fig. 4, shows a type of receiving system for the reception and regularization of reversed-phase Morse code signals.

Fig. 5, illustrates the manner of application of reversed-phase A. C. Morse code signaling 95 for establishing a superimposed communicating system on a submarine cable normally operating with direct current.

Fig. 6, shows a method for producing reversed-phase A. C. cable code signals by 100 operating on an alternator field.

Fig. 7, shows types of A. C. cable code signals produced by the system of Figure 6, and the effect of rectifying such signals.

Fig. 8, is adapted to describe how, by the 105 use of a commutator, suitable currents are produced for the purpose of establishing synchronism between receiving apparatus and the received alternating current.

Fig. 9, shows a complete equipment adapted 110 to receive alternating current cable code signals by means of a rectifying commutator.

Fig. 10, shows an alternative system for receiving A. C. cable code signals by means of alternating-field relays instead of rectifying commutator.

Fig. 11, depicts a method for producing 5 A. C. cable code signals of very constant frequency without the use of a rotating alternator.

Fig. 12, shows a governor adapted to control 10 the speed of a motor-driven alternator for the production of constant-frequency cable code or Morse code signals.

Fig. 13, shows a method for driving an 15 automatic transmitter forming the signals in step with an alternator producing the signal current.

Prefatorially, it may be remarked that 20 British Patents Nos. 176,827, dated Oct. 11, 1920, 178,873, dated Oct. 29, 1920, and 203,045, dated May 31, 1922, describe various methods 25 of utilizing trains of alternating current as signal elements in the multiplex transmission of signals. The common signaling code utilized in connection with such systems is the Morse code, wherein the signal elements consist of dots and dashes which are distinguished from each other by the difference in duration of the signal impulses comprised by the trains of alternations. Spaces between 30 signal elements commonly comprise a mere absence of alternating current. In the operation of such systems it is commonly found that there is a tendency for the train of alternations to persist after the termination of a 35 signal element, and since spaces are supposed to consist of a mere absence of alternating current, it becomes necessary to make the spaces long enough actually to realize a condition of zero current. The possible speed 40 of signaling is therefore reduced because of the tendency of the alternations to persist. The growth of a signal is not instantaneous, either as measured in terms of the current itself or in terms of the movement of a device 45 used in the reception of the signals, and this condition adds to the difficulty brought about by the persistence of effects after the proper time for signal termination, as previously mentioned.

50 In accordance with the present invention it is proposed to transmit (in Morse dot and dash code) each successive signal element by alternating current reversed in phase to that used for the preceding signal element. The 55 small alternations persisting after one signal element will then be neutralized by the small preliminary alternations of the following signal element, and a definite zero condition will therefore be secured at the instant when the 60 two trains neutralize each other. The space between signal elements, can, therefore, be shortened, resulting in a higher rate of signal formation.

If at the receiving end the alternating current 65 be rectified at the instants when the cur-

rent passes through its zero values, the direction of the rectified current impulses will reverse when the phase of the alternating current fed to the rectifier reverses, and consequently the direction of deflection of any ordinary type of galvanometer coil connected to the rectifier will reverse also. Deflection in one direction can be interpreted to mean a dot in a signaling code and deflection in the reverse direction to mean a dash, so that by 70 these means, therefore, it becomes possible to operate the alternating current signaling system in a fashion analogous to the ordinary "cable code". The considerable time involved 75 in the production of long dashes is not required, and the speed of signaling is increased by from 20 to 30 per cent by this feature alone. Since, in cable code working, there is no necessity for spaces between signal elements, they need not be inserted at the sending end except for letter and word spaces. The cross over from one phase position representing dots, say, to the opposite phase position representing dashes can be made directly without an interposed idle period, and the utilization of this method of "block" 80 signaling results in a still further increase in speed.

As previously pointed out, the application 85 of the invention to Morse code working consists in causing successive signal elements to be constituted by current whose alternations are in opposite time-phase position to those of the preceding signal.

The arrangement shown in Figure 1 is designed to accomplish this result. The method shown is based upon British Patent No. 202,784, dated June 15, 1922, Figures 5 and 6, but has incorporated in it a relay device 100 for reversing successive signals. At 1 is the armature of an alternating current generator, terminating in leads 2 and 2' from which current is delivered to whatever transmission system may be involved. Signals are produced by making and breaking the current in the alternator field winding 3. A battery or source 7 provides direct current for excitation of field 3, and intermediate the source 7 and field 3 is a reversing switch 6, which controls the direction of current 105 through the field winding. Resistance 5 and condenser 4 are provided for controlling the field current as described in British Patent No. 202,784, dated June 15, 1922. The initial formation of signals is at key 10, which may be a hand key or automatic transmitter, and this key controls the magnet 12 connected to the battery 11. On signaling, armature 13 is attracted by the magnet 12 against the restraining force of spring 15, and the armature carries with it the head 14 which consists of insulating material. The downward motion of the head 14 allows lever 17 acting under the force of spring 17' to make contact at 17'. On making this contact, field 3 110

is energized by current flowing from battery 7 through the reversing switch 6, leads 20, 21, and 19. (It is to be noted that in the downward or signal position the head 14 breaks contact between 16 and 16'.) During the excitation of the field 3, alternating current signals are delivered from armature 1 by way of leads 2 to the system transmitting or utilizing them.

- 10 Upon opening key 10 at the termination of a signal the head 14 moves upward, first allowing contact to be made between 16 and 16', and then slightly later breaking the contact 17 and 17', thus interrupting the circuit between battery 7 and field 3. The current existing in field 3 persists because of the self inductance and dies away in the closed circuit through lead 19, contacts 16 and 16', lead 18 and resistance 9.
- 15 The winding 8 of a polarized relay controls the operation of reversing switch 6, and the winding 8 is connected in parallel with resistance 9 by leads 8' and 8''. At the termination of a signal, when contact 16-16' is established, the relay winding 8 is thus energized by the decay current from field 3, and when thus energized the relay acts to move the reversing switch 6 into its opposite position. The connection between battery 7 and field 3 is thus reversed during an idle period following a signal, and since the succeeding signal will be in an opposite direction the switch 6 will be moved back into the original position when this signal terminates. Thus, 20 the switch 6 operates after every signal by the field discharge current, so that each signal is represented by current through field 3 opposite in direction to the current of the preceding signal. As is well known, reversal of field current in an alternator reverses the phase of the output, so the desired result is accomplished.

The advantage, previously mentioned, of using successive reversals of phase in Morse signals will be apparent from a consideration of Figure 2, which shows the results normally obtained with existing apparatus and results as obtained by using apparatus as described in Figure 1. In this figure the shaded blocks in curve A represent two dots in Morse code, being the E. M. F. impressed on the field system of an alternator as shown in Figure 1 by the operation of contacts 16-16' and 17-17' when no reversal in direction is accomplished (that is, without making use of the present invention). The dots occur between times O and t^1 , and t^2 and t^3 , with a space between t^1 and t^2 . The field current grows and dies away slowly, so that between the instants t^1 and t^2 it does not have time to vanish completely before a new growth is started by the beginning of a second dot at time t^2 .

Curve B shows the corresponding output E. M. F. of the alternator and it is seen that

the E. M. F. still persists at time t^2 when growth consequent upon the second dot begins. The minimum cyclic value of E. M. F. in curve B occurs at time t^2 , but even there the E. M. F. by no means vanishes, so that 70 the two trains of alterations which should constitute separate dots are scarcely distinguished separately; they merge one into the other.

Curve C shows the E. M. F. for two dots 75 in Morse code as impressed on the field 3 of the alternator in Figure 1 by the arrangement there described. The dots are in opposite directions, as represented by the shaded areas, being of the same duration and having the same spacing as in the case of curve A. Curve D of Figure 2 shows the resulting output E. M. F. of the alternator. From the beginning, O to t^2 the output curve D is identical with curve B, but at t^2 the second dot begins in a reversed direction, so that the E. M. F. curve D is forced to become zero before it builds up again to form the second dot. This is to be observed at the time marked S where a definite space occurs between the two trains of alterations constituting separate dots.

The curve D, because of the definite space S represents a satisfactory working state of affairs, whereas the curve A, because of the 95 lack of definition, does not. To be made workable, the time between dots in curve A would have to be prolonged in order to secure their separation, and therefore a slower signaling speed would result than in the case 100 of curve D, which, as pointed out, is satisfactory.

The above analysis of the effect of successive phase reversals has been based upon the production of alternating current trains by 105 operation upon the field of an alternator, but the same description applies in the case of any kind of system transmitting or utilizing the alternating current trains, and wherein building up and dying away of the alternating current take place comparatively gradually. This is the case in any type of resonant system, and the whole advantage of reversed phase signaling for Morse code working depends upon the bettering of the definition 110 between signals as described.

An alternative type of apparatus for reversing the phase of successive signals is shown in Figure 3, and the type there described does not depend for its action upon the discharge current from an inductive circuit (as the alternator field winding) as is the case in Figure 1. In Figure 3 the reversing switch is placed between the alternating current source and the output circuit so that phase reversals do not depend, as in Figure 1, upon the reversal of field excitation. In Figure 3, 23 is the alternating current source and 24 are the output leads, which must be connected to the source 23 in successively op- 115

posite sense consequent upon signals formed at the transmitter or key or the like, 31. At 28 is a reversing switch operated by a polarized relay whose winding is 29. A battery 30 operates through this reversing switch and the key 31 to effect the motion of either one of the two polarized relays 22 and 25. Those two latter relays are oppositely polarized so that one or the other operates depending upon the direction of current in their two series-connected winding 22° and 25°. A bias, as by springs 22''' and 25''' is imposed on the armatures of the respective relays so that contact is normally maintained against the upper contacts 22'' and 25'', thus short-circuiting leads 24 when no signal is passing. The winding 29 of the reversing switch (relay) is connected through leads 32 and 34, and condenser 26 and resistance 27, across the main relay windings 22° and 25°, the latter being connected by way of lead 33 through the reversing switch and battery to key 31.

Beginning with the reversing switch 28 in its upper position, a closure of key 31 sends current from battery 30 upwards through windings 25° and 22°, thus deflecting, say, the upper armature 22 to make contact at 22''. This connects source 23 to leads 24 in one direction. The condenser 26 has meanwhile become charged (its charging current confirming the previously existing upward position of switch 28) to the potential of battery 30. Upon releasing the key the discharge current from condenser 26 flowing through coils 22° and 25° flows also through winding 29 and causes the reversing switch 28 to pass to its downward position. Armature 22 loses its deflection and the leads 24 are again short circuited at the termination of the signal. Everything is now as it was originally except that the switch 28 is reversed, so that the next signal will reverse the current in windings 22° and 25°, causing armature 25 to deflect and thus produce a reversal of phase between the source 23 and the output leads 24. These actions take place repeatedly, causing successive signals to be sent out first through relay 22 and then through relay 25, establishing a reversal of phase in the alternating current supplied over leads 24 from alternator 23 for each signal, as desired.

It has so far been shown how to produce the reversed-phase alternating current Morse code signals, and it remains to describe methods for effectually receiving them. One method for doing this is described in British Patent No. 218,361 dated Mar. 27, 1923, for in the method there described the act of reception is dependent upon the heating effect of the received alternating current signal; and this is independent of whether the phase of successive signals is reversed or not.

Another method for receiving the re-

versed-phase Morse code signals is shown in Figure 4. In this figure, the arriving alternating current signals enter at leads 35 and pass into the coil 36 of an ordinary "fork relay". The coil 36 carries a light air-damping vane 36' and is supported between the poles N and S of a magnet by the usual stretched wire or fiber suspension 37, 38 and bridge piece 39. The coil 36 carries also the two antennæ 40 of gold wire or the like which are electrically joined together and which play between the two metal butts 41, the butts also being electrically joined together, but mounted far enough apart so that the antennæ 40 do not touch them when the coil 36 is stationary. An arriving alternating current signal causes the coil 36 to vibrate and the antennæ 40 to make contact successively against the two butts 41, thus repeatedly establishing connection between leads 42 and 43 joined to the antennæ and butts, respectively. A battery 46 acts through the butt-antennæ contact by way of leads 42' and 43' to operate a more powerful relay whose main winding is shown at 47. 90 A condenser 44 in series with a resistance 45 connected between leads 42 and 43 serves to minimize the effects of the small interruptions to the circuit between butts and antennæ when the latter are vibrating under the 95 action of an arriving alternating current signal. Substantially steady current from battery 46 is thus maintained through relay winding 47 as long as the train of alternations constituting a signal lasts. 100

The relay winding 47 may be that of any ordinary relay suitable for the operation of any subsequent receiving device of usual type, such as a siphon recorder as shown, comprising coil 56, siphon 57 attached thereto, and paper slip 58, the recorder being actuated by current from battery 51 through contact 50' and relay tongue 50. It is preferred, in this connection, to employ a modified form of relay to operate contacts 50 and 50', because the signals established by the antennæ 40 and butt 41 contacts consequent upon the passage through coil 36 of alternating current signals similar to those shown by curve D of Figure 2, may be of somewhat 115 irregular duration, so that it becomes desirable to provide means for making the final signals, as recorded, more regular. The relay tongue 50 is held by a magnetic bias, or by a spring 49, normally against the upper 120 contact 50'', but the action of signal current through the main winding 47 causes tongue 50 to make contact against 50'', thus sending a signal to the recorder 56. In addition to the main winding 47 there is provided an 125 auxiliary winding 48 in the relay. Auxiliary winding 48 is connected through resistance 52 and condenser 53 across contacts 50' and 50'', as shown. Lead 51' connects one side of battery 51 to the tongue 50. The 130

other side of battery 51 is joined through lead 60, recorder coil 56, and lead 59 to contact 50', and also through a resistance 55 and an inductance 54 to contact 50".

5 Beginning with a condition of no signal, when tongue 50 rests against contact 50", a signal arrives and starts current from battery 46 through main winding 47, deflecting tongue 50 to contact 50', starting a signal at recorder 56. Condenser 53 then begins to charge through resistances 52 and 55 and auxiliary coil 48, and connections to the auxiliary coil are so made that this condenser current on discharging tends to establish the tongue contact at 50' still more firmly, so that even though the signal current through the main winding 47 vanished, the auxiliary coil would still maintain the contact until the charging current into condenser 53 became 20 so small as to release tongue 50 against the action of the bias 49. By suitably adjusting resistance 52 and condenser 53 (as well as resistance 55) the instrument can be made to produce a minimum length of signal, thus 25 ensuring that no dot becomes so short as to be ineffective in operating the recorder 56. When tongue 50 moves back against stop 50" at the end of a signal, the discharge of condenser 53 through the auxiliary winding 48 maintains that contact until the discharge current becomes small, and therefore the arrangement as described operates to ensure that no space shall be less than some minimum length of time. The action as above 30 described is extremely useful in practice, effecting a marked improvement over signals as would be received without its aid from a receiving relay of the vibrating-coil type, 36, 40 and 41. In adjusting the resistance 52 and condenser 53 of the auxiliary winding 48, care must be exercised that the sum of the compulsory minimum marking and spacing times does not exceed the total time period of the elementary received signals; 35 otherwise failure to reproduce the signals results. The relay contacts 50, 50' and 50" are shown as operating a recorder 56, but they may be used for any of the usual purposes well known in the art, for example, in 40 place of recorder coil 56 and inductance 54 there may be substituted the two magnet windings of the usual perforating apparatus, used for recording the signals in the form of perforated paper taps, etc.

55 The methods of reversed-phase alternating current signaling herein described are particularly advantageous in telegraphy over submarine cables where, because of the transmission properties of the cable, it is usually necessary to work the alternating current system at a low frequency. As a consequence of the low frequency a rapid rate of signal formation can only be secured by limiting the number of alternations or cycles per sig-

nal element to a minimum; and this in turn necessitates the use of devices as herein described. Further, the alternating current signaling system is of value in submarine cable telegraphy principally when it is used as a channel, or channels, of communication superimposed upon the usual or ordinary direct current working of the cable.

Figure 5 illustrates two cable stations adapted to operate for communication between them with reversed-phase Morse code signals, while one of the stations is equipped also with usual direct current apparatus for communicating with a third station also connected to the same cable. In Figure 5, 1, 1', and 1" represent the cable joining three stations, X, Y, and Z; Z being a remote station not shown in the figure. Stations X and Y are equipped with A. C. (alternating current) apparatus as described for communicating with each other, and station X is also equipped with D. C. (direct current) apparatus for communicating with station Z. Both sets of communications, Z-X and X-Y can be carried on in both directions (duplex) and simultaneously. The essential features of the systems shown in Figure 5 have been described in British Patent No. 203,045 dated May 31, 1922, so that they need only be briefly mentioned here. At station X where both A. C. and D. C. sending and receiving apparatus are provided, there are: *i*, the cable; *b*, the duplex bridge with apex at *a*; "transient moderator", or filter circuits, *c*, *c'*, and *c''* for the purpose and as described in British Patent No. 203,045 dated May 31, 1922; *d*, the armature of a direct current generator for producing D. C. signals as described in British Patent No. 202,784 dated June 15, 1922; and *e*, the armature of an alternator with its field winding *e'* arranged for the production of reversed-phase A. C. signals as described in connection with Figure 1 hereof. The two sources *d* and *e* work in series as described in British Patent No. 202,784 dated June 15, 1922. For receiving there is provided the usual D. C. receiving apparatus *g*, connected across the duplex bridge, and there is also provided the artificial line *j*. The A. C. receiving apparatus is connected to the duplex bridge through a condenser *k*, including auxiliary balancing means *h* and *h'* as described in British Patents Nos. 201,603 dated Apr. 8, 1922 and 203,045 dated May 31, 1922. Tuned circuit *l* has magnetic coupling *m* with tuned circuit *n*, the latter connecting through a condenser *o* to amplifiers *p* and *p'*. A relay system *r* as described in connection with Figure 4 hereof is connected to amplifier *p'* through transformer *q*. The relay system *r* may be used to operate any desired further devices as described under Figure 4. Station X is thus equipped to send and receive D. C. signals,

and simultaneously therewith to send and receive reversed-phase Morse code alternating current signals.

Station Y is joined to the cable i' and i'' through a condenser S. This station is equipped to utilize only A. C. signals for duplex communication with station Z. At A is the apex of a duplex bridge B, and to balance the bridge, condenser S' simulates condenser S, and artificial lines J' and J'' simulate the cables i' and i'' extending in either direction from station Y. The A. C. transmitting system connected to apex A is similar to that of station X, containing "transient moderator" C, C' and C'', with an alternator E and its field E' arranged to produce reversed-phase alternating current signals as described in Figure 1 hereof. The A. C. receiving system is identical with that of station X, comprising condenser K in the connection to the duplex bridge, tuned circuit L, magnetic coupling N to tuned circuit N, condenser O, amplifiers P and P', and transformer Q between the last amplifier and the receiving device R. In this case a form of receiver R is shown which consists of the ordinary siphon recorder, the coil of which carries the alternating current signals. It records on the usual paper tape T the trains of alternations of the type shown in curve D of Figure 2, which are thus made available for visual interpretation. Station Z at the remote end of the cable i'' is provided with the ordinary duplex D. C. equipment for communicating with station X. The foregoing description of the system shown in Figure 5 is included here to illustrate a type of practical application of the reversed-phase alternating current signaling method, and this completes the description of the methods employed in adapting the invention to Morse code working.

The other, and perhaps the more important application of reversed-phase alternating current signaling is for the production and utilization of "cable code" signals in an alternating current signaling system. In this code, dots and dashes are represented, in ordinary direct current working, by positive and negative current, respectively; but to accomplish a similar distinguishing feature in alternating current signals, which are in themselves made up of positive and negative half cycles of current, it becomes necessary to introduce means for producing and interpreting a reversal of phase in the alternating current constituting the signal elements. The advantages to be gained by this method of signaling arise partly from the fact that "cable code" is a shorter code than "Morse code," and partly from other considerations to be described later.

Figure 6 shows an electric generator 61 having its field 62 connected to the control

circuit comprising condenser 63 and resistances 64 and 65, and further connected to the conventional type of cable code transmitting key 66, 66', and 66'', and a battery or source 67. The arrangement is identical with that described in Figure 3 of British Patent No. 202,784, dated June 15, 1922, except that in this case the armature 61 is that of an alternating current generator. 68 and 68' are the output terminals by which the signals are delivered to the system transmitting and utilizing them. The action of the system shown in Figure 6 will be described in connection with Figure 7, which shows the types of signals produced. Curve A in Figure 7 represents the field excitation 80 of the alternator in Figure 6, and comprises dot a^1 space a^2 , dot a^3 , space a^4 , and a dash a^5 , the dash being represented by field current negative, whilst the dots are represented by positive field current. Curve B represents in 85 full line the E. M. F. output of the alternator at terminals 68 and 68'. If the dot key were depressed over the full time represented in the curves, a steady alternating E. M. F. represented by the full line b^1 , dotted line b^2 , 90 full line b^3 , dotted line b^4 , and dotted line b^5 , would be produced. When the keys are manipulated in accordance with curve A, the full line of curve B is produced, causing alternating E. M. F. at b^1 to represent a dot, a 95 zero output as a space at b^2 , an alternating E. M. F. output of unchanged phase for another dot at b^3 , zero for a space at b^4 , and finally an alternating E. M. F. output of reversed phase as shown by the full line b^5 representing a dash. The dots and dashes are distinguished, therefore, by a reversal of phase.

In cable telegraphy it is common practice to use "block" signals in cable code working. That is, a succession of signals of one sign (as dots) are run together into one long period of positive current, the number of dots contained therein being determined by the duration of the prolonged signal. Similarly it is with dashes, and useless spaces are thereby eliminated. In Figure 7, curve C shows how curve A may be shortened by using "block" signals. The dot, dot, dash of curve A are placed in immediate juxtaposition, becoming c^1 , c^2 , and c^3 , and the time required for the complete signal is shortened in the ratio of T^c , the unit signal time in curve C, to T^a , the unit signal time in curve A. When the alternator field is excited in accordance with curve C then its output E. M. F. is as shown by curve D, the two dots d^1 and d^3 appearing as a continuous train of alternations, but the dash b^5 appearing in full line as an alternating E. M. F. reversed in phase from the dot E. M. F. This is indicated by the dotted line d^5 which shows the E. M. F. which would be produced if d^5 were a dot instead of a dash.

The visual interpretation of signals recorded in the form of curve D would be practically impossible, but if the alternating current signals D be passed through a commutator or reversing switch operating synchronously with the alternator, and reversing the signal current at the zero instant in every half cycle, the current delivered by the commutator will appear as in curve E. The dots e^1 and e^3 appear as a train of positive impulses, and the dash e^5 as a train of negative impulses, and when this commutated current is passed through a relay or any usual type of recording instrument having a little inertia to carry it over the short gaps between the impulses, a record will be obtained from the current of curve E similar to curve C, which is the ordinary type of block signal in common use.

The solution of the problem of cable code alternating current signaling thus consists in the provision of means, as shown in Figure 6, for forming the reversed-phase cable code signals and in the provision of means, such as a synchronous commutator, for interpreting the cable code A. C. signals of the type shown in curve D of Figure 7. Since the transmitter is at one end of the cable and the receiving apparatus at the other end of the cable, it is necessary, when the cable code A. C. signals are received through the medium of a reversing commutator, to provide means for keeping the receiving commutator running synchronously with the arriving alternating current, so that a result typified by curve E in Figure 7 may be secured. If the alternating current comprising a signal be purely sinusoidal and be commutated at the instants of peak value, the current delivered by the commutator will have an average value of zero, and hence will not deflect an ordinary type of moving coil galvanometer or a relay. In Figure 8, curve A shows alternating current signals, a dot at a^1 and a dash at a^2 , reversed in phase from a^1 . Curve B shows the current (or E. M. F.) derived from A by commutating curve A at the times p^1 , p^2 , etc. corresponding to the peak values. The average value of the curve B is seen to be zero, as mentioned, both for the dot b^1 and for the dash b^2 . Curve C shows the result of commutating curve A at times q^1 , q^2 , etc. delayed by an angle θ behind the times p^1 , p^2 , etc. of peak values. The resulting commutated dot current c^1 has a positive average value represented by the dotted line c' . This average value c' is consequent upon the delay θ in the action of the commutator, and by passing the current through a relay, actions can thus be brought into play to hasten the commutator action and cause its reversals again to take place at the peak instants of curve A. Conversely, if the times q^1 , q^2 , etc., of commutation occur ahead of the peak instants, the average current c' would be nega-

tive, and the relay thus oppositely affected thereby, would cause the commutator to be retarded. The commutator thus employed for establishing the synchronizing action would be rigidly connected to a commutator operating in time quadrature therewith, the latter commutator then serving to commutate the received signal current at the zero instants as described in connection with Figure 7, curve E for the production of signals.

It will be noted from Figure 8 that the effect of a delay θ in the instant of commutation produces a negative average current c'' during a dash a^2 , whilst it produces a positive average current c' during a dot a^1 . If so the action of this commutator (hereinafter termed the "synchronizing commutator") through a relay is to determine the direction of phase correction (to remove the delay θ) by the direction of the average currents c' and c'' , it is obvious that either, one of the currents c' corresponding to a dot, or c'' corresponding to a dash, must be eliminated so as not to affect the subsequent relay and thus destroy the synchronizing action established by the other; or else both currents must be made to affect the subsequent relay in the same way consequent upon the phase error θ . This latter is readily accomplished by interposing a switch between the relay which utilizes the current from the synchronizing commutator for the purpose of phase correction and the synchronizing commutator itself. This switch is operated by the signals (of the type shown in curve E of Figure 7) themselves in such a way as to send the synchronizing currents c' and c'' of curve C, Figure 8, through either one of a double winding provided in the synchronizing relay, the direction of connection of these windings being made so that both currents c' and c'' produce similar effects consequent upon the delay θ in commutator action.

Figure 9 shows diagrammatically a complete receiving system for cable code, alternating current signals. The system shown is based upon the use of two commutators, one commutating the received current at the zero times as shown in Figure 7 for the formation of rectified signals, and the other commutator commutating the current at, or about, the peak value as shown in Figure 8 for the purpose of actuating apparatus to be described for maintaining synchronism between the commutator actions and the received alternating current. The two commutators will hereinafter be referred to as the "signal commutator" and the "synchronizing commutator" respectively. In Figure 9, at 69 are the leads coming from the transmission system, over which arrive the cable code alternating current signals to be received. At 71 is the signal commutator, and at 73 is the synchronizing commutator, both mounted on the same shaft 76, and so adjusted as to oper-

ate at times one-fourth of a cycle apart. Brushes 70 and 70' conduct the signal current to commutator 71, and brushes 74, and 74', in parallel with brushes 70 and 70' respectively, convey a portion of the signal current to commutator 73. The rectified current from commutator 71 is delivered by way of leads 77 and 77' from brushes 72 and 72' to the siphon recorder 78 and 78', which recorder is of the usual type and serves to write the signals on a paper tape 79. An inductance 80 in series with the recorder serves to suppress the pulsations existing in the rectified signal current. A further impedance 81 or any other combination of resistance, inductance, capacity, etc. as is well known in the art may be used to "shape" the received signals. The tape record 79 is the final form in which the signals are received, but it is readily seen that in place of recorder 78 any usual type of relay may be used for sending the signals out over another circuit, or to operate an automatic perforator, etc., such devices being well known in the art.

The synchronizing commutator 73 takes a portion of the received signal current and delivers it, after commutation, through brushes 75 and 75' and leads 88 and 88' to further apparatus whose function is to keep the shaft 76 and the two commutators running synchronously with the alternating current received. A relay 91 relay carrying two windings 89 and 89' (the windings having resistance shunts 90 and 90' as may be required) is supplied with the commutated current over leads 88 and 88', but between the relay 91 and the synchronizing commutator 73 is interposed another relay 82 whose purpose is to ensure that the commutated current corresponding to dots is delivered to one winding, say 89, of relay 91, while the commutated current corresponding to dashes is delivered to winding 89'. This is for the reasons set forth in the description of Figure 8. Relay 82, with its series inductance 86 and shaping circuit 87 is similar to, and connected in parallel with, the recorder 78, but instead of carrying a siphon it carries the antennæ 83 of gold wire or the like which play between the metal butts 84 and 84'. When dots are received, contact is made by antennæ 83 with butts 84, and when dashes are received contact is made with butt 84'. Thus, by way of butts 84 and 84' and leads 85 and 85' the current from the synchronizing commutator delivered by way of lead 88' to the antennæ 83 is caused to pass through relay coil 89 or relay coil 89' depending on whether dots or dashes are being received over input leads 69.

When the commutators 71 and 73 act in the wrong phase position with reference to the arriving alternating current, a current as typified by c' in Figure 8 affects relay 91, causing antennæ 93 to make contact with butt

94 when the commutator operates too late, and with butt 94' when it operates too early. The antennæ 93 are very delicate and their contact with the butts is unsuited to the control of large currents, so by means of battery 97, magnets 98 and 98', and leads 95, 96 and 96' more powerful relay contacts 99 and 99' are actuated by relay 91. Dumping vane 92 is provided to relay 91, preferably moving in a viscous fluid to make the movement of relay 91 sluggish, as has been found best in practice. Finally, therefore, when contact 99 closes, it is because the action of the commutators 73 and 71 is delayed, and when contact 99' closes it is because the commutators act too early, and these contacts are to be made to actuate mechanism designed to remove the phase errors in the commutator actions. The methods employed for doing this are similar to those described in British Patents Nos. 196,971 dated Jan. 4, 1922, and 213,302 dated Oct. 28, 1922, so that they need not be described here in great detail.

A vibrating reed 108 of any usual and suitable type, maintained in vibration by a battery 111 and magnet 110, drives a phonic motor 107 through leads 112, contacts 109, and battery 111. The phonic motor 107, through gearing 106 and 105, and shaft 103, carrying a damping (such as a mercury-filled) fly wheel 104, drives a differential gear 100, and through it the shaft 76 carrying the two commutators 71 and 73, which are thus driven at a steady speed. The frame 101 carrying the idler pinions of the differential gearing 100 has mounted on it a worm wheel 102; the whole is rotatable and controlled by the worm 114 driven (through gears if necessary, but not shown) by the armature 113 of a direct current motor whose field 115 is continuously excited by source 116. The motor 113 is connected by leads 117 to the two relay tongues 120 and 120' arranged with battery 121 and resistance 122 to act in the manner of a common cable code hand key to send current over leads 117 to motor 113 in either direction depending upon which of keys 120 or 120' is actuated by its controlling magnet 119 and 119'. Magnets 119 and 119' are energized by battery 118 acting through relay contacts 99 and 99' respectively, and leads 123. Therefore, when relay contact 99 closes because of a late commutator action (as previously described), magnet 119 is energized, tongue 120 is deflected, and current from source 121 is sent through the armature 113 in one particular direction. This causes the armature to rotate, and with it the worm 114, which in turn rotates the worm wheel 102 and frame 101, thus advancing the phase of shaft 76 and the commutators so as to remove the previously existing phase error. When the commutators reach their proper phase position the deflections of relays 91, 99, and 120 cease,

- and motor 113 stops running. Similarly, the motor 113 is driven in the opposite direction when relay 99' closes consequent upon an early action of the commutators. At the 5 completion of each correction the motor 113 is brought quickly to rest by the short circuit to its armature through leads 117 and contacts 120 and 120', because the field 115 remains fully excited.
- 10 The above completes the description of the necessary synchronizing and receiving functions, but in order to minimize the number of phase corrections required a control is provided to the vibrating reed 108 driving 15 the phonic motor 107 so as to eliminate those speed errors which cause deviations in phase (of the commutator action) to accumulate. Extending beyond the end of the vibrating reed 108 is a weak spring 124 constrained at 20 some point along its length by the two stops 125 mounted in a sliding block 126. The sliding block 126 is moved backwards or forwards by the screw 127 operated by the toothed wheel 128 under the action of one 25 or the other of pawls 129 or 129'. Pawls 129 and 129' are operated respectively by magnets 130 and 130', which in turn are energized by battery 118 through relay contacts 99 and 99' respectively and leads 131. When 30 contact 99 closes because of a retarded commutator action, magnet 130 is energized and pawl 129 moves down, turning wheel 128 and screw 127 in such a way as to move the butts nearer to the reed and thus increase 35 the rate of vibration of the latter. This action takes place in addition to the phase correction through motor 113 previously described, and tends to eliminate the speed error which caused the phase error to accumulate. Opposite action through contact 40 99' and pawl 129' takes place when the commutator advances in phase because of the reed vibrating too rapidly.
- Additionally the usual manual adjustment 45 of the reed is also preferably provided, this adjustment being of particular advantage when setting the apparatus in operation since any unduly appreciable lack of synchronism can by these means be roughly 50 eliminated when the apparatus will automatically make the further requisite fine adjustment in the manner described. In this manner synchronism is more quickly established than would otherwise be possible.
- 55 There are, of course, numerous modified forms for the apparatus described. The reed correction might be done as described in British Patent No. 213,302 dated Oct. 28, 1922, by gearing screw 127 directly to worm 60 114. In place of the small spring 124 a small weight might be arranged to slide along the reed. In place of starting and stopping the motor 113 for phase corrections, a reversing clutch might be used in connection with a 65 steadily rotating shaft. In place of commu-
- tators of the "commutator" type as shown, cam- or eccentric-operated switches might be used. In place of using two separate coils in relay 91, a single coil might be used with the direction of current through it controlled by relay 82. Various arrangements of well known types of relays can be utilized to perform the same, or analogous, functions as those shown. In practice, because of distortions in wave shape of the received alternating current, it is found to be advantageous to set the two commutators 71 and 73 not exactly in quadrature, but at a slightly different angle. All such modifications are deemed to fall within the present invention, and are held to be useful modifications to be used as preference or circumstances may dictate. 70
- Another method may be adopted for receiving the cable code A. C. signals. British Patent No. 205,843 dated May 25, 1922, describes a relay having an alternating field, through the action of which a one-way deflecting force is exerted on the relay coil carrying an alternating current signal. British Patent No. 196,971 dated Jan. 4, 1922, 80 shows a method for maintaining the alternating excitation of such a relay in synchronism with the received current. By the provision of an intermediate relay to perform functions analogous to those of relay 82 in Figure 9, a system based upon British Patent No. 196,971 dated Jan. 4, 1922, and as shown in Figure 10 can be used for receiving cable code A. C. signals through the medium of an alternating-field relay instead of through the medium of a rectifying commutator and ordinary relay. In Figure 10, A. C. signals arrive over leads 132, are passed, if necessary, through a transformer 133, and thence over leads 134 and 134' to the relay winding 135 whose field 136 is excited by alternating current locally produced and kept in synchronism with the arriving signal current. This is the signal relay, its field excitation being maintained in phase with the arriving signal 90 current. It deflects one way or the other for the dots and dashes in the arriving signals of the type shown in curve D Figure 7. Antennæ 135' mounted on the coil 136 are normally in contact with both butts and constitute the apex of a Wheatstone bridge containing resistances 141, 141', 139, and 139' and battery 140. The said bridge is balanced and remains balanced until movement of coil 135 breaks contact between antennæ and one 100 of the butts. Current then flows through leads 142 and 143 forming the bridge cross-arm, and through siphon recorder coil 151 and polarized relay coil 150. Dots and dashes break contact at butts 137 and 137' respectively, thus unbalancing the bridge 141, etc. in opposite directions, and causing siphon recorder 151 with its ink reservoir 145, siphon 151', and paper tape 152 to write the signals. The relay coil 150 controls the motion of a 110 105 115 120 125 130

reversing switch 154 through the relay tongue 153, so that the switch occupies one position when dots are received and the other when dashes are received. This receiving switch has a function analogous to that of relay 82 in Figure 9, in that it serves to make similar the effects of dots and dashes (their current) upon relay 156 which is used to maintain synchronism between the alternating source used for exciting the relay fields 136 and 160 and the received alternating current. Relay coil 156 is connected through leads 155 and 155' through reversing switch 154 to leads 134 and 134', and is thus in parallel with relay 135. Relay coil 156 carries antennae 157 adapted to make contact on deflection with butts 158 and 158', and thus through leads 159 to actuate a phase correcting device 162 controlling alternator 163, either as described in British Patent No. 196,971 dated Jan. 4, 1922, or by means of a differential gearing as described in Figure 9 hereof, or in any similar or suitable manner, to keep alternator 163 in synchronism with the arriving signal current. Alternator 163 has its field 164 permanently excited; it is a two phase alternator, and by way of brushes or terminals 146, 147, 148, and 149, and leads 165, 165', 166, and 166' excites the primary winding 167 of an adjustable-phase transformer. Relay winding 160 of the synchronizing relay is excited by way of leads 165-165' of the alternator, and relay field 136 of the signal relay is excited by way of leads 169 from the secondary 168 of the adjustable-phase transformer. Excitation of relay fields 136, and 160 should be substantially in quadrature, but the phase-adjusting transformer 167-168 provides for changes from this condition if found desirable. The action here would be analogous to adjusting the commutators 71 and 73 of Figure 9 at a position different from right angles, as referred to previously.

In Figure 10 the siphon recorder 151 might be replaced by a relay for operating other kinds of well known receiving apparatus. Numerous other modifications are possible within the principle of the present invention, and such modifications are deemed to be included as part of the present invention.

A further method for operating the signal relay and the synchronizing relay is based upon the use of two bolometer bridges, polarized by locally produced alternating current, and thermally affected by the received signals. This type of bridge is described by Irwin in British Patent No. 29,206 of 1910, and it is only necessary in this connection to utilize two of such bridges, polarized by locally produced alternating currents in phase quadrature with each other, and operating ordinary types of relays to supplant the relays 156 and 135 of Figure 10.

From the foregoing it is evident that the re-

ception of reversed-phase, cable code alternating current signals is dependent upon maintaining synchronism between the received signal current and some local operation at the receiving station. To do this it is essential that the received signals are comprised of current of very steady, constant frequency. Figure 11 shows a method of producing A. C. cable code signals of very constant frequency. At 170 is a vibrating reed maintained in vibration by the circuit 171 in the usual way. Battery 173 is connected to the reed and by leads 173' to one side of each of two coils 177 and 177'. Contacts 172 and 172' on either side of the reed connect to straps 174 and 174' respectively of a cable code key. The contact levers 175 and 175' of the key connect respectively to the other sides of the two coils 177 and 177', through resistances 176 and 176'. Condensers 178 and 178' are placed across the respective coils 177 and 177', and each coil has magnetic coupling, 185 and 185' respectively to a coil 179; but the coupling between coils 177 and 177' themselves is negligible. Coil 179 is included in a tuned circuit including coil 181 and condenser 180 and resistance 180'. A further coil 183 having magnetic coupling 182 with coil 181 has its terminals 184 and 184' connected to the system designed to transmit or utilize the signals. When key 175' is depressed, the alternate contacts at 172 and 172' supply impulses to coils 177 and 177' from battery 173, and through the tuned intermediate circuit 179, 180, 181, and 180' the impulses produce an alternating E. M. F. in coil 183 which is transmitted by way of leads 184 and 184'. Resistance 180' serves to determine the intensity and decrement of the oscillations produced. When key 175' is depressed, alternating E. M. F. of opposite phase is produced at terminals 184 and 184', thus providing for the production of dashes, whilst the depression of key 175 produces dots. The system thus described is complete in itself, producing alternating current of a steady frequency, determined by the rate of vibration of the reed, without requiring an alternating current generator of the rotating type.

A particular advantage of a system of this type when used in connection with combined alternating and direct current signaling systems resides in the fact that by virtue of the tuned circuit 179, 180, 180' and 181 being inductively associated with the generating source and output circuit the formation of alternating current signals is effected without the production of transient uni-directional current impulses which would tend to disturb direct current receiving apparatus at the remote end of the transmission system.

If it be desired to use an alternator, as shown in Figure 6, to produce the signaling current for cable code working, then it is desirable to govern its speed so as to keep it

running in synchronism (or a multiple thereof) with a vibrating reed, because of the constancy of frequency of the latter. Figure 12 shows a form of governor adapted to do this.

5 At 187 is the armature of a direct current motor, driving the shaft 186 to which is connected the signaling alternator whose speed is to be controlled. At 188 is the motor field, excited by source 189 through series resistances 190 and 190', and it is by means of the resistance 190 that the controlling effort on the motor speed is exerted. A shaft 192, either the motor shaft itself or gear-driven thereby if necessary, carries a drum comprised of two metal members 193 and 194, configured as crown gear wheels with pointed teeth, the teeth of the two members being forced tightly together but insulated from each other by pressed mica insulation, or the like. This drum rotates with shaft 192, and on its periphery has bearing against it a sliding contact or brush 201 arranged to traverse across the face of the drum, parallel to the shaft, by means of a pivot joint 200.

25 Brush 202 establishes electrical contact with one member 194 of the drum, whilst member 193 is completely insulated. Brushes 201 and 202 are connected by leads 204 and 203, respectively, across resistance 190, and by rotation of the drum 193-194, resistance 190 is momentarily short circuited by brush 201 making contact with drum member 194. The short circuit is continuous when brush 201 rests on member 194 at the right hand end of 30 the drum, and does not exist at all when the brush is on member 193. The effectiveness of the successive short circuits depends, therefore, on the position of the brush along the face of the drum, and thus by changing the field excitation of the motor, the motor speed is controlled by the position of brush 201. Further mechanism is now employed to control the position of brush 201 so as to keep the motor 187 and its alternator running 45 synchronously with the vibrating reed. At 191 is a phonic motor of usual type, driven by a vibrating reed, not shown in the figure so that its speed is steady. 191' is the shaft of the phonic motor, and it carries on its end 50 one main gear of a differential gearing 197; the other main gear of the differential is carried by shaft 195, the latter being a prolongation of shaft 192. The two shafts and their gears run in opposite directions, and therefore any difference in their speeds is communicated to the ring 196 carrying the idler pinions of the differential gearing. Motion 55 of the ring 196 of the differential is communicated by link member 198 to lever 199 to effect the motion of brush 201 along the face 60 of the drum in such a direction as to restore equality between the speeds of shafts 195 and 191'. A spring 205 acts on lever 199 to take up any lost motion in the mechanism, and 65 stops 206 and 207 are provided to prevent excessive motion of ring 196 and brush 201. When these stops come into play because of excessive speed differences between shafts 195 and 191', then the comparatively weak phonic motor 191 will be driven at other than 70 its normal speed by shaft 195 acting through the differential gear, but this is of no consequence, as it does not occur in normal running. Perfectly steady running of motor 187 and its attached alternator is thus established, and this is an essential to cable code 75 A. C. working as described previously.

In practical telegraphy it is necessary to preserve a record of outgoing signals, and in cable code A. C. working this is conveniently 80 done by driving a small commutator or rectifier contacts by the signaling alternator shaft, a portion of the outgoing current thus being rectified and subsequently delivered to an ordinary siphon recorder to establish the desired record of the signals.

Further, it is of distinct advantage in either kind of alternating current signaling herein described (Morse or cable code) to have the transmitter forming the signals 85 driven at a steady speed, and preferably driven in step with the alternating current source so that every signal contains exactly the same number of alternating current cycles (or multiples thereof when Morse code 90 dashes or block cable code signals are involved). A convenient way to attain this synchronous running of transmitter and alternator is shown in Figure 13. At 208 is the alternator armature supplying signals over 95 leads 209. The shaft 208' of the alternator carries a cam 210 operating contact levers 212 and 212' on electric contacts 211 and 211' respectively. These contacts then produce 100 impulse currents from battery 215 and lead 214 through leads 213 and 213' respectively to operate a usual type of phonic motor 216. This phonic motor acts through gearing 217 to drive the automatic transmitter 218, controlling, as described in Figure 6, the delivery of 105 current from battery 219 to alternator field 220 for the formation of signals. By suitably choosing the gearing 217, any desired number of alternator cycles can thus be used in each 110 signal element. If a generating system as shown in Figure 11 is employed, then the phonic motor can be driven from auxiliary contacts operated by the vibrating reed in the usual manner, and the desired relation between the alternating current cycles and the 115 formation of signals at the transmitter thus secured.

Whilst it will be understood from the foregoing description and appended claims that the invention is in no way limited in application to systems using cable code signals it is to be noted that this invention makes it possible for cable code signals to be utilized in alternating current signaling systems, certain 120 practical embodiments being described and 125 130

illustrated herein. This constitutes an important departure in the art and particularly in submarine cable telegraphy utilizing multiplex systems.

5 I claim:

1. In alternating current signaling systems utilizing a signal code composed of different types of signal elements constituted by currents of different phase, means for producing change of phase in the alternating current, signals constituted by such current, said signals applied to receiving apparatus and said apparatus incorporating means for commutating the received current.
- 10 2. In alternating current signaling systems utilizing a signal code composed of different types of signal elements constituted by currents of different phase, means for producing change of phase in the alternating current, signals constituted by such current, said signals applied to receiving apparatus and means carried by said apparatus for reversing each current alternation near the zero instant in every half cycle.
- 15 3. In alternating current signaling systems, means for producing change of phase in the alternating current, signals constituted by said current, said signals applied to receiving apparatus and said apparatus incorporating means for commutating each current alternation near the peak values thereof.
- 20 4. In alternating current signaling systems means for producing change of phase in the alternating current, signals constituted by said current, said signals applied to receiving apparatus, said apparatus incorporating means for commutating each current alternation near the peak value thereof, the currents resultant upon said commutation applied to synchronizing apparatus and said apparatus establishing commutation as nearly as possible at said peak values.
- 25 5. In alternating current signaling systems means for producing change of phase in the alternating current, signals constituted by such current, said signals applied to receiving apparatus, said apparatus incorporating means for commutating each alternation near the peak values thereof, synchronizing apparatus for establishing commutation as nearly as possible at said peak values, and the angle of departure of commutation from such values determining the resultant corrective current applied to said synchronizing apparatus.
- 30 6. In alternating current signaling systems, means for changing the phase of the alternating current, signals constituted by said current, said signals applied to receiving apparatus, said apparatus incorporating means for effecting phase reversals near each zero instant of each received current alternation and means for commutating said alternations near the peak values thereof, a corrective current produced by departure of

commutation from the peak values, said latter current applied to synchronizing apparatus and said latter apparatus maintaining synchronism between the apparatus for effecting current reversals at each zero instant and 70 such instants in the incoming signals.

7. In alternating current signaling systems, means for producing change of phase in the alternating current, signals constituted by said current, said signals applied to receiving apparatus, two commutators associated with said apparatus, said commutators arranged in time phase quadrature, one of said commutators commutating the received current near the peak values thereof and the 75 other of said commutators commutating said current near the zero values thereof.

8. In alternating current signaling systems, signals constituted by the alternating current, said signals in part distinguished 85 from one another by change of phase in said current, said signals composed of two types of elements and applied to receiving apparatus, means associated with said apparatus for commutating the received current near 90 the peak values thereof, two corrective currents produced consequent upon departure of commutation from said values, the corrective currents produced by one type of element being in a direction opposite to the corrective currents produced by the other type of element, means for constituting one unidirectional current from said corrective currents and means for applying such unidirectional current to synchronizing apparatus for establishing and maintaining synchronism at 95 said peak value.

9. In alternating current signaling systems, signals constituted by the alternating current, said signals composed of a plurality 105 of different types of elements, means for producing change of phase in said current at pre-determined intervals in the formation of said signals, receiving apparatus to which the signals are applied, means associated with said apparatus for commutating the received alternations near the peak values thereof, corrective currents produced consequent upon departure of commutation from said peak values, the direction of the corrective current 110 at any instant dependent upon the type of element received, all of the corrective currents applied to a relay, said relay functioning to combine all of said corrective currents into one uni-directional current, said latter current applied to synchronizing apparatus and said apparatus maintaining commutation as nearly as possible at said peak values.

10. In alternating current signaling systems, signals constituted by the alternating current, means for producing phase reversal 125 of said current at one end of each successive signal, said signals applied to receiving apparatus, said apparatus incorporating a polarized relay, the incoming signals applied to 130

- the coil thereof, antennæ carried by said coil said antennæ co-acting with butts to energize a second relay coil and said latter relay operating recording apparatus.
- 5 11. In alternating current signaling systems signals constituted by the alternating current, said signals composed of two elements, said elements in part distinguished from one another by phase reversal of said 10 current, said signals applied to receiving apparatus said apparatus incorporating two commutators in time phase quadrature, one of said commutators commutating the received current near the zero values of the alterna- 15 tions thereof, the output of said commutator applied to two relays, one of said relays recording the signals, the other of said relays energizing one coil of a double coil relay, the other coil of said latter relay energized from 20 the commutator commutating the signals near the peak values of the alternations thereof, departure of commutation from the peak and zero values producing unbalanced currents in said two coil relay, such latter cur- 25 rents producing deflection of the relay coil and deflection of said coil actuating synchronizing apparatus to establish and maintain commutation as nearly as possible at said peak and zero values.
- 30 12. In alternating current signaling systems as claimed in claim 11 deflection of said two coil relay operating one of two contacts, each of said contacts operating relays, said relays varying the period of vibration of a 35 vibrating reed, said reed operating a phonic motor and said motor driving the commuta- tors.
13. In alternating current signaling systems as claimed in claim 11, a pair of contacts adapted to be operated by the deflection of 40 said two-coil relay, said contacts closing the circuit of an electric motor, operation of one contact producing rotation of the motor in one direction and operation of the other contact producing rotation of the motor in the opposite direction, said motor driving a train of differential gearing and said gearing inter- 45 posed between the phonic motor and the commutators whereby operation of said gearing varies the phase of the commutators relative 50 to that of the phonic motor.
14. In alternating current signaling systems, signals constituted by the alternating current, means for producing phase reversals 55 in said current, said signals applied to a relay, deflection of said relay effected by the signals in one of two directions dependent upon the type of signal element received at any instant, a second relay operated by the first relay for recording the signals, a revers- 60 ing switch, said switch applying the alternating signal currents in phase to a correcting relay, the field of said latter relay energized from a local alternating current source, lack 65 of synchronism between said source and the signal currents producing deflection of said correcting relay and said deflection applying a corrective effort to establish synchronism.
15. In a telegraph signaling system, a di- 70 rect current signaling system in combination with an alternating current signaling system and means for producing change of phase in the alternating signal current.

FREDERICK EUGENE PERNOT.
